UNITED STATES PATENT OFFICE.

RUDOLF E. HELLMUND, OF PITTSBURGH, PENNSYLVANIA, ASSIGNOR TO WESTINGHOUSE ELECTRIC AND MANUFACTURING COMPANY, A CORPORATION OF PENNSYLVANIA.

MOTOR-CONTROL SYSTEM.

1,285,160.

Specification of Letters Patent. Patented Nov. 19, 1918.

Application filed June 11, 1915. Serial No. 33,482.

To all whom it may concern:

Be it known that I, RUDOLF E. HELLMUND, a subject of the Emperor of Germany, and a resident of Pittsburgh, in the 5 county of Allegheny and State of Pennsylvania, have invented a new and useful Improvement in Motor-Control Systems, of which the following is a specification.

My invention relates to systems of control for single-phase alternating-current motors of the compensated doubly-fed type, and it has for its object to provide means whereby a large number of evenly graded accelerating steps may be obtained by the use of comparatively few control switches and preventive devices.

In the accompanying drawing, Figures 1, 3, 12, 14, 16 and 18 are diagrammatic views of single-phase motors, together with their 20 attendant supply and control circuits, illustrating different forms of my invention; Figs. 2, 4, 13, 15, 17 and 19 are sequence charts illustrating the method of switch operation in the attendant control systems; 25 Figs. 5 to 11, inclusive, are simplified diagrammatic views showing in detail the method of switch operation employed in connection with the circuit of Fig. 1; Figs. 20 to 27, inclusive, are similar views, explanatory of Fig. 18; and Figs. 5^a, 11^a, 12^a, 14^a and 16^a are simplified diagrammatic views illustrating the distinctive features of the accompanying control systems.

In the operation of single-phase alternating-current railway systems, it has been found highly desirable to employ motors of the commutator type because of the flexibility of speed control attendant upon apparatus of this character. Various systems have 35 been developed whereby a motor of the character described may be accelerated in a smooth and gradual manner and, at the same time, the commutating field strength may be adjusted to such values as to minimize 40 sparking and to eliminate the necessity for auxiliary spark-suppressing devices, such, for example as resistance leads to the commutator.

In the design of control systems of the 50 character above specified, it is necessary to employ a considerable number of control switches, each of which entails expense, weight and complication and it is furthermore necessary to employ several resistance

members for series connection in the motor 55 circuit to reduce the motor current and for eliminating transformer short circuits when changing over from one transformer tap to another.

By my invention, I reduce the number of 60 control switches to a minimum and, furthermore, use the same resistance member or members repeatedly to perform different functions in the acceleration of a motor of the character described. 65

Referring to the form of my invention shown in Fig. 1, I have shown a source of alternating current at 20, such, for example, as the secondary winding of a railway vehicle transformer. A motor 21 of the compensated commutator type is arranged for energization from the source 20 and comprises an armature 22, a main field winding 23 and a cross field winding 24. Suitable control switches 1 to 8, inclusive, and resistance members 25, 26 and 27 are employed in accelerating the motor 21 in accordance with the sequence chart of Fig. 2, the proper sequence being maintained by any suitable means, either manual or automatic. 70 75 80

Referring to Fig. 2, it will be seen that, at the outset, switches 1, 2 and 6 are closed, the armature, the main field winding 23, the cross field winding 24 and the resistance member 25 are all connected in series relation between the tap 1 and the tap 6, and the armature 22 is short circuited through the member 26 for repulsion operation, all as indicated in Fig. 5. In the accelerating step 2, the switch 4 is closed, eliminating the resistance member 25 from the circuit and therefore increasing the motor current, as indicated in Fig. 6. The switch 3 is then closed, introducing an intermediate tap for the doubly-fed connection, as shown in Fig. 95 7, and, immediately thereafter, the switch 2 is opened, establishing the doubly-fed connection shown in Fig. 8. In the accelerating positions 5, 6 and 7, the switches 6, 7 and 8 and the resistance member 27 are manipulated to change the motor connection from the tap 6 to the tap 8, thus increasing the voltage applied to the cross field winding 24, as indicated in Fig. 9. The resistance member 25 is now reintroduced and employed as a preventive device in shifting the intermediate connection of the motor from the tap 3 to the tap 5, as indicated in 100

105

accelerating steps 8, 9 and 10, and the resistance member 25 is finally short circuited, as shown in Figs. 10 and 11.

It will be seen from the above explanation 5 that the resistance member 25 is employed both as a series-connected rheostat and as a preventive device in raising the voltage and that its use in both relations is controlled by exceedingly simple connections. A smooth 10 and well balanced acceleration is obtained, as is indicated in the last column of the chart of Fig. 2 wherein the steps indicated by A are pure acceleration steps; those indicated by R are suitable for running; and 15 those indicated by T are merely transition steps and are never maintained for any appreciable length of time.

Referring to the form of my invention shown in Fig. 3, the general system of connections is the same as indicated in Fig. 1 20 with the addition of a resistance member 28, connected in shunt relation to the member 25 and controlled by a switch 9. As will be evident from Fig. 4, the additional 25 resistance member 28 renders possible two additional accelerating steps 2 and 12 illustrated, in detail, in Figs. 5^a and 11^a, respectively. The system of operation is otherwise strictly analogous to that shown in 30 Fig. 1.

The form of my invention shown in Fig. 12 is the same as that shown for Fig. 1 and, in addition, another transformer tap 9 is provided for the intermediate tap. The acceleration is the same as indicated in connection with Fig. 1, the resistance member 25 being employed first in series relation before operating as a doubly-fed motor on the tap 3, then being employed as a preventive device in the transition from the tap 3 to the tap 5 and finally, being employed again as a preventive device in the transition from the tap 5 to the tap 9, the destructive transition connection being 45 shown in Fig. 12^a.

In the form of my invention shown in Fig. 14, what may be termed a sub-repulsion operation is employed, in that the armature winding is not short circuited as in 50 the ordinary repulsion motor, but is connected to the source so that current is passed therethrough in the opposite direction from that employed in the ordinary compensated motor as described and claimed in my co-pending case, Serial No. 33,481, filed June 11, 1915, and assigned to the Westinghouse Electric & Manufacturing Company. At the outset, by closing the switches 1, 12, 3 and 6 as shown in Fig. 14^a, the armature 22 55 is connected to the line in a reverse direction from that ordinarily employed, the main field and cross field windings are connected in series relation through the resistance member 25, and a minimum voltage is 60 applied to the main and cross field windings

in series through the tap 6 through the resistor 25. The resistance member 25 is now eliminated by closing the switch 4 and opening the switch 12. The switch 5 is next closed, establishing an intermediate tap. At 70 the fifth accelerating step, the switch 3 is opened, thus connecting the main field and armature windings in series relation. The switch 12 is next closed, eliminating the member 25 from the intermediate tap and 75 permitting efficient doubly-fed operation. By the manipulation of the switches 6, 7^a and 8 and the member 27, the voltage applied to the cross field winding is now raised in the ordinary manner. Next, by the manipulation of the switches 12, 4, 5 and 5^a 80 and of the member 25, the voltage applied to the intermediate tap is raised, as indicated in Fig. 1. It will be particularly noted in connection with the system of Fig. 85 14 that the armature current is maintained at a minimum in starting, by connecting the main and cross field windings in series, the cross field in this type of apparatus being 90 provided with twice the number of turns of the armature winding, and, later on, when normal operation is attained, the current is increased by connecting the main field winding in series with the armature. 95

The system of Fig. 16 is similar to that of Fig. 14 but differs in that the switch 4, controlling the direct connection between the main and cross-field windings is eliminated and, at the outset, the motor windings are 100 all connected in series rather than with the connections employed in Fig. 14, as shown in Fig. 16^a. The remaining operation is similar to that set forth in detail.

In the system of Fig. 18, my invention is 105 shown as applied to a motor of the compensated commutator type, wherein, at the outset, the main field winding is excited by the difference between the armature and the cross field exciting currents. On the first accelerating notch, the switches 1, 2^a, 13 and 6 are closed, short circuiting the armature winding through the main field winding and energizing the cross field winding with a minimum voltage from the tap 6 through the 110 resistance member 26, as indicated in the accelerating step 1 in Fig. 19 and in Fig. 20. The member 26 is then eliminated by closing the switch 11, as shown in Fig. 21. The initial step toward the setting up of a 115 doubly-fed connection is now taken by introducing a connection from the inner terminal of the cross field winding 24 to the tap 5, (step 3) (Fig. 22) and the armature and cross field windings are next disconnected by opening the switch 13, (step 4) 120 (Fig. 23). Another step is then taken in establishing the doubly-fed connection by closing the switch 4 (Fig. 24) connecting together the upper terminal of the main field winding and the inner terminal of the cross 125 130

field winding, the common connection receiving current from the tap 5 through the member 25. The short circuit of the main field winding on the armature is now removed (Fig. 25) by opening the switch 2^a and, in the next step, (Fig. 26) the member 25 is eliminated and doubly-fed connection is established. From this point on, the acceleration follows the established practice in 10 that the switches 6, 7 and 8 and the member 27 are manipulated, as shown in steps 8, 9 and 10, to shift the outer lead of the cross field winding 24 from the tap 6 to the tap 8 to obtain a voltage increase (Fig. 27). 15 In like manner, the voltage on the intermediate tap is finally raised by the manipulation of the switches 3, 4, 5 and 5^a and the member 25 so that energy is finally supplied from the tap 5^a to the intermediate 20 connection, and the typical doubly-fed connection shown in Fig. 28, with maximum voltage on all parts thereof, is provided.

While I have shown my invention in a plurality of distinct embodiments, it is obvious to those skilled in the art that it is susceptible of various minor changes and modifications without departing from the spirit thereof, and I desire, therefore, that no limitations shall be placed thereupon except such as are imposed by the prior art or are specifically set forth in the appended claims.

I claim as my invention:

1. The combination with a compensated commutator motor, of a control system therefor including an impedance member, means

for first inserting said member between the armature and cross field windings of said motor, and means for thereafter employing said member as a preventive device in adjusting the voltage supplied to said motor. 40

2. The combination with a source of alternating current, of a dynamo-electric machine of the single-phase commutator type provided with a cross-field winding, and means providing connections from the terminals of said machine to said source and from an intermediate point of the machine circuit to said source, said means comprising an impedance device and switching apparatus whereby said device may, at times, be employed to increase the impedance of the main motor circuit, at other times, may be short-circuited, and at still other times, may be repeatedly employed as a bridging member in adjusting the voltage supplied to said intermediate connection. 50 55

3. In a control system, the combination with a multi-voltage-tap source of single-phase current, a compensated commutator motor adapted to be connected thereto, severable leads from the armature and main field windings to a pair of source taps, suitable leads from the cross field winding to another pair of source taps, and an impedance device with a short circuiting device therefor connected between a tap in one pair and a tap in the other pair. 60 65

In testimony whereof, I have hereunto subscribed my name this 29th day of May 1915. 70

RUDOLF E. HELLMUND.
